HYDROCARBON FUEL BURNING DEVICE

Eugene E. Goller and Lee R. Foster, Chicago, Ill.,
assignors to Unique Manufacturing Co., Inc.,
Chicago, Ill., a corporation of Illinois

Application March 8, 1943, Serial No. 478,440

4 Claims. (Cl. 158—70)

The invention relates to a fuel burning device adapted for burning various types of hydro-carbon fuels and especially for burning treated, leaded or "ethyl" gasoline. The invention contemplates a device wherein the heat for vaporizing the liquid fuel is transferred indirectly through the walls of the device, with combustion taking place inside the flame nozzle of the device at a point above the fuel level in the fuel preheating and vaporizing chamber with which the flame nozzle is connected, while the vaporizing heat or heated vapor is conducted downwardly within the walls of the vaporizing chamber to a point beneath the open end of the mixing tube or member, whose upper open end communicates with the flame nozzle or member.

The improved device provides a method of conducting the vaporizing heat into the fuel which permits a very close control of the generator temperature, a vital factor in the successful burning of leaded or "ethyl" gasoline.

Furthermore, since all vaporizing heat must travel through the burner wall and be transferred to the fuel holding chamber by conduction, the amount or degree of heat may be accurately controlled by providing the tube or flame nozzle of the device with a predetermined number and size of slots or holes.

Another object of the invention is the provision of a comparatively large annular fuel holding chamber arranged in the walls of the device which enables the burner to operate at a very low generator temperature. As a result of the structure and condition mentioned, namely by having a comparatively large volume of liquid fuel warming up during operation and replacing the escaping or burning vapor, the necessity for a high heat in any part of the generator proper is obviated and deposits of carbon, lead, bromine, sulphur and other solids are practically eliminated, because these products are carried along with the vapor and expelled with the flame of the device.

The invention has for its object the provision of a burner for the fuels mentioned which is so designed that the generator temperature is controlled to equal or match the vaporizing range of the fuel being used; or in other words, the device is constructed to provide substantially the same temperature conditions which are employed to produce the fuel at the refinery, with the result of maintaining the top generator temperature the same as the end point of the fuel, the burner vaporizes all of the fuel without reaching a tem-

perature which would change the chemical composition of the fuel.

The objects and above enumerated advantages of the invention, as well as other advantages inherent therein, will all be readily comprehended from the detailed description of the accompanying drawing wherein:

Figure 1 is a vertical sectional view of one form of the improved device with certain portions shown in elevation and an intermediate portion of the fuel supply line broken away.

Figure 2 is a similar view of a modification or silent type burner device.

The particular exemplification of the invention disclosed in Figure 1 is in the nature of a Bunsen burner and it will be understood that it is to be connected with a suitable source of liquid fuel under pressure or introduced by a suitable fuel pump; the liquid fuel being conveyed to the device by the pipe 10, provided with a suitable control or shut-off valve 11. Burners of the type to which the invention relates preferably are arranged in a vertical position, in order that the vapor may hold down the raw fuel and prevent it from entering the burner outlet or flame tube.

The supply pipe 10 communicates with the bottom of the annular fuel chamber 12 which is arranged in the cylindrical wall of the device and is adapted to hold a comparatively large quantity of the liquid fuel. The fuel chamber 12 is formed by the outer cylindrical wall 13 whose upper end is shown bent or curved inwardly at 14 and is united with the cylindrical flame nozzle 15, which preferably is of predetermined diameter and vertical height, with the lower end of the nozzle 15 constituting the inner wall of the fuel holding chamber, as shown at 16. The fuel holding chamber 12 is closed at its bottom except for an opening 17 with which the supply pipe 10 communicates; and the lower end of the flame nozzle 15 is provided with a closure diaphragm or annular wall 18 having a central opening to receive and hold an upstanding mixing tube or flue 19 which preferably extends to a point slightly above the plane of the normal level of the liquid fuel in the chamber 12 indicated in Figure 1. The mixing tube is open at both ends, with its upper end discharging centrally into the flame nozzle 15, while the lower open end is arranged a predetermined distance above the vapor nozzle 20, provided with the discharge port 21. The vapor nozzle 20 is provided with an upwardly disposed tube 22 which extends upwardly through the bottom of the fuel cham-

ber—preferably diametrically opposite the fuel supply port or opening 17—to a point beneath the top 14 of the fuel chamber and also preferably slightly beneath the plane of the top of the mixing tube 19; the upper end of the vapor conveying tube 22 extending above the normal level of the liquid fuel and communicating with the vapor gathering portion or chamber in the upper end of the fuel receiving chamber 12.

In the construction described, the comparatively large quantity of liquid fuel in chamber 12 is preheated and caused to vaporize by the indirect transfer of heat to the fuel in chamber 12, mainly by heat conduction through the metal walls of the flame nozzle 15 whose lower end wall is shown preferably somewhat reduced in thickness and constitutes the inner wall of the annular fuel chamber. This method of conducting the heat into the liquid fuel permits a very close control of the generating temperature, which is a vital factor in the successful burning of leaded or "ethyl" gasoline; the degree or amount of conducted heat being regulated or controlled by a reduction in wall thickness of the flame nozzle which may be accomplished by providing the nozzle with one or more extraneous slots or sockets, as shown at 23 in Figure 1, of predetermined size and which extend part way into the wall or entirely therethrough. This conduction of heat may, of course, be differently accomplished, but the use of sockets or slots (whose number and size may be varied) enables a more accurate and close control of the amount of heat. The annular fuel chamber 12 enables the preheating of a comparatively large quantity of liquid fuel which fills the chamber to a point beneath the top of the vapor take-off tube 22 and consequently provides a vapor chamber above the liquid fuel; the vapor being discharged by port 21 into the lower end of the mixing tube 19, with entrained air; combustion taking place inside the flame nozzle at a point above the fuel level in the fuel chamber 12.

Figure 2 illustrates, in vertical section, a modified form or silent type burner. Basically, this burner is the same as the Bunsen or torch type heretofore described and involves the chambered member 24, shown circular in cross-section (although member 24 as well as member 13 may be of any suitable cross-section) provided with a fuel chamber 25 closed at the top by wall 26 and at the bottom; the chamber being formed by the inner wall 27 (preferably heavier than the outside wall) which may be formed integral with the end walls of the member or intimately secured thereto. The bottom of the member is provided with a port 28 and with the supply line or pipe 10, similar to the supply pipe in Figure 1, and provided with a control valve. The bottom of member 24, preferably at a diametrically opposite point, is apertured for passage of a vapor tube 22, whose lower end connects with the vapor nozzle 20 provided with discharge port 21. The lower end of the member 24, centrally, is provided with a closure diaphragm 18 which in turn supports the lower end of a mixing tube or flue 29 which preferably extends somewhat above the top of the member and through a central opening in the heating plate 30 whose outer perimeter is flanged or bowed upwardly as shown at 31. This plate 30 may be integrally secured, at least to the inner wall 27 of the member 24, or any other suitable manner of attaching the plate may be employed whereby the heat from plate 30 may be transferred to the metallic walls 24 and 27 in

order that the liquid fuel in chamber 25 may be properly preheated and vaporized prior to the passage of the vapor into vapor tube 22.

The same low generator temperature, as in the previously described structure, is used and the temperature range controlled by the thickness of the heating plate, by the diameter of the plate, and the extent and angle of the flange 31; while overheating may be avoided, when necessary and in keeping with the character of the liquid fuel used, by providing the plate with slots or holes of predetermined size and number.

In the particular embodiment shown in Figure 2, the upper end of the mixing tube 29 is shown internally threaded to receive the externally threaded ring 32 secured to the flange spreading hollow inverted cup shaped member 33 whose upper and lower walls are held in proper spaced relation and secured together by suitable spacing braces, one of which is shown at 34. The top wall of the member 33, on its lower face, may be provided with an inverted cone shaped spreader as at 35 whose apex extends slightly downward into the ring 32 and hence into the path of the upwardly rising products of vaporization, causing the products to pass annularly toward the perimeter of the flame spreading member 33 whose outer annular portion extends downwardly into contact with the heating plate 30; the downwardly disposed portion of the upper plate of member 33 being provided with a plurality of holes or slots as shown at 36; the curved flange 31 of the heating plate causing the flame to spread upwardly.

The burner shown in Figure 2, similar to the type shown in Figure 1, preferably is maintained and operated in vertical position to enable the vapor to restrain or hold down the raw fuel and prevent it entering the burner outlet member 40 although it may be possible to position the burner differently.

By varying the height of the burner outlet tube, it is possible to vary the temperature of the escaping vapor, the higher the tube, the hotter the vapor, and the shorter or lower the tube, the colder the vapor; an extremely short or low tube would result in picking up wet fuel.

We have shown the burner in Figure 2 provided with an inverted vapor spreader 35, but this spreader may be omitted in the structure shown without interfering with the proper operation of the burner.

The burners shown in both Figures 1 and 2, as is usual with hydrocarbon fuel burners, are provided with a priming pan or cup, as shown at 37, to receive a small quantity of liquid fuel for the purpose of preheating the burner during initial operation, namely when the burner is in a cold state. The priming pan or cup is preferably adjustably secured to the supply pipe 10 by means of the collar and set-screw, as shown at 38.

We have shown what we believe to be the simplest embodiments of our invention wherein vaporization of the liquid fuel is produced by heat transferred through certain metal walls of the device, but certain modifications may be possible without, however, departing from the spirit of our invention as defined by the appended claims.

What we claim is:

1. A hydro-carbon fuel burning device comprising a chambered member adapted to hold a comparatively large quantity of hydro-carbon fuel and provide a vapor holding chamber in its upper

end, said member being formed with a central opening therethrough, the inner wall of said member terminating above the vapor chamber in a flame directing portion while the lower end of said wall constitutes a fuel heating and vaporizing portion; an open-ended mixing flue of uniform diameter arranged lengthwise in said opening in spaced relation with the inner wall of said member; an apertured closure diaphragm for the lower end of said central opening secured to said inner wall and to the lower end of said mixing flue whereby the latter is secured in place and held spaced from said inner wall; a fuel supply pipe connected with the bottom of said fuel holding chamber; and a vapor tube communicating at one end with said vapor holding portion of said chamber while the other end is spaced from the lower end of said mixing flue and provided with a vapor discharge port directed toward the end of said flue.

2. A hydro-carbon fuel burning device comprising a double walled member adapted to hold a quantity of fuel and provide a vapor chamber therein above the fuel, the inner wall of the member constituting the fuel heating and vaporizing means and extending above the vapor chamber and terminating in a flame directing portion, said member being provided with an opening disposed lengthwise therethrough; a fuel supply pipe connected with the fuel receiving portion of the chamber; an open-ended mixing flue disposed through the opening in said member in spaced relation with the inner wall of said member; means whereby said flue is maintained in place and air passage between the flue and the inner wall of said member prevented; and a vapor tube arranged in said chamber with its upper end communicating with the vapor holding portion of said chamber while the other end is disposed beneath and spaced from one end of said flue and provided with a discharge port directed toward said end of the flue.

3. A hydro-carbon fuel burning device comprising a main member provided with spaced vertical walls united at top and bottom to provide a closed fuel holding and vapor chamber therebetween extending throughout the height of the member, the member being formed with a central opening; a fuel supply pipe connected with

the bottom of said chamber at one side of the member; a vapor take-off pipe disposed through the bottom of said chamber and terminating in the upper end of the chamber, the lower end of said take-off pipe being disposed in spaced relation beneath the central opening in said member and provided with an upwardly directed vapor discharge port; a mixing flue arranged vertically in said central opening in spaced relation with the inner wall of the fuel holding chamber and above said vapor discharge port; a flame directing member disposed above and intimately secured to said main member in heat transmitting relation therewith and adapted to receive the mixture of air and fuel vapor from the mixing flue; and means whereby the lower end of said flame directing member is closed and said flue is held in spaced relation with the inner wall of said chamber.

20 4. A hydro-carbon fuel burning device comprising a main member with spaced vertically arranged walls to provide an annular liquid fuel holding chamber therebetween closed at top and at bottom, said member having a large central opening therethrough; a liquid fuel supply pipe connected with the bottom of the fuel holding chamber at one side of the device; a vapor take-off pipe extending upwardly through said chamber to the vapor space in the upper end thereof, the lower end of said pipe being arranged beneath and spaced from said member and provided with an upwardly directed vapor discharge port; an open ended mixing flue arranged in said central opening in spaced relation with the inner wall of said member; means secured to the bottom of said member and to said flue for closing said central opening and for supporting the flue in place; a flame directing member secured to the top of the main member in heat conducting relation therewith; a double walled inverted cup-shaped member secured to the upper end of said mixing flue with its perimeter disposed on said flame directing member and provided with openings adjacent its perimeter, the inner wall of said 30 40 45 inverted cup-shaped member being provided with an opening communicating with the upper end of said mixing flue.
